UNITED STATES PATENT OFFICE.

WARREN TRAVELL, OF NEW YORK, N. Y.

HOIST AND TRANSPORTING APPARATUS.

1,318,467.

Specification of Letters Patent.

Patented Oct. 14, 1919.

Application filed March 25, 1919. Serial No. 284,896.

To all whom it may concern:

Be it known that I, WARREN TRAVELL, a citizen of the United States, residing at New York, in the county of New York and 5 State of New York, have invented certain new and useful Improvements in Hoist and Transporting Apparatus, of which the following is a specification.

This invention relates to improvements in 10 hoisting and transporting apparatus, more particularly it relates to such apparatus in which a counterweight is employed, the purpose of the invention being to provide for the use of a counterweight in such manner as to balance the bucket, and a part of 15 its load, if desired; to apply the counterweight also to the transporting rope with some advantage in the operation of the carriage from which the bucket hangs; to make 20 a running shift from the hoisting to the transporting functions; to obviate wear on the rope and other apparatus, particularly in the larger machines where the ropes travel either at high speed, or carrying heavy 25 stresses; and to provide the other advantages that characterize the invention. The invention accomplishes this by providing what are virtually two extra drums, one on the shaft of or connected with the drum that 30 operates the carriage rope, and the other on the shaft of or connected with the drum that operates the hoist or holding rope, and by hanging the counterweight in a bight of rope whose ends are wound, one on each 35 of these two extra drums; all being so arranged that the extra drums are coupled together during the traverse action of the carriage but not during the hoisting.

In consequence, when all are coupled, the 40 hoisting rope and the carriage rope run upon or from their drums together and at equal speed, and the counterweight rope merely shifts from one of the extra drums to the other without changing the length of 45 its bight. This is the traverse action, in which the carriage moves, carrying the load, but the load and counterweight make no change of elevation.

When said drums are uncoupled, however, 50 the carriage drum is held by a brake; and the turning of the hoist drum raises or lowers the load while the movement of its associated drum correspondingly changes the length of bight holding the counter-

weight. Upon the drums being coupled together, as by application of a friction clutch, the carriage begins to move at the same speed as the hoist rope, so that the load ceases to change its elevation; and co-incidentally both ends of the counterweight 60 rope come to move alike, so that the length of bight stops changing, and change in elevation of counterweight ceases.

It is intended that the patent shall cover, by suitable expression in the appended 65 claims, whatever features of patentable novelty exist in the invention, disclosed. Two forms of apparatus are set forth hereinafter, as an illustration of how the invention may be applied. In the accompanying 70 drawing, which shows embodiments of the invention:

Figure 1 is a diagram partly in plan and partly in elevation, with the divisions between plan and elevation indicated by small 75 breaks in the rope lines; and

Fig. 2 is a similar diagram, partly in plan and partly in elevation, of a modification.

Referring to Fig. 1 of the drawing, 10 indicates a way, such as an I-beam, which 80 may be fixed, or may be movable, as a boom, on which runs a carriage 11 whose position thereon is controlled by a traversing rope 12. This rope, although having two separate portions, functions as a unit and is 85 herein treated as if it were single and not broken at the carriage but merely attached thereto. At the outer extremity of the way, this rope goes about a sheave 13, and at the inner extremity of the way it is suitably 90 guided to a traversing drum 14 to which both of its ends are fastened; so that a rotation of the drum 14 pulls the rope and so 95 pulls the carriage in one direction or the other; and on stopping of the drum the carriage 11 may be held stationary, by the application of any suitable brake to the drum, as at 15. The carriage 11 has a sheave 16 over which a hoisting or holding rope 17 runs to its depending bucket or other load 100 17a. For this as well as for other parts of the apparatus any desired or suitable form of reeving of ropes may be employed, many methods being already known. The hoisting rope 17 is suitably guided inboard to a hoisting drum 18 which may be equipped with a 105 brake 19. The drums 14 and 18 are represented as being arranged on parallel shafts,

mounted in bearings 20 and carrying gears 21, 22, meshing together and a clutch 23 so that these drums can either run in unison or be separated. Suitable driving means, 5 such as an electric motor, indicated at 25, may communicate power through gear 26 to the hoist drum 18. In operation, the hoist drum will run with the traverse drum if the clutch 23 be closed and will run alone 10 if the clutch 23 be open, the traverse drum 14 being then held stationary by its brake 15. In the embodiment of the invention illustrated in Fig. 1, an additional drum 24 is 15 mounted rigidly on the same shaft with the carriage drum 14, and an additional drum 28 is mounted rigidly on the same shaft with the hoisting drum 18. These two drums 24, 28, may in practice each be mere continuations of the drums 14 and 18, or, if preferred, they may be arranged otherwise than 20 on the said shafts, but rigidly connecting to the carriage and the hoisting drums respectively as by gearing or otherwise. A counterweight rope 27 has one end attached to drum 24, and the other to drum 28, each of its end portions being so wound upon the drum to which it is attached that when those drums run coupled together, the rope 27 winds on one and unwinds from the other. 25 In the particular manner of reeving illustrated in the diagram, the section of rope intervening between these drums has a bight in which is a floating sheave, 29, to the becket of which is attached a rope 30 which 30 passing over suitable guide sheaves sustains a counterweight 31.

When the apparatus is stationary, the pull 40 of the counterweight transmitted through the two limbs of the bight to the two drums 24 and 28 pulls on the drum 24 in direction opposite to that in which the carriage rope 12 pulls on the drum 14, and it will be observed that the weight of the bucket and its load, hanging on rope 17 over sheave 16 on 45 the carriage, tends to pull the carriage inward along the way 10. The stress thrown upon the brake 15 in holding or controlling the carriage is therefore reduced materially by the counterweight 31. The other limb of 50 the bight pulled by the counterweight is connected to the drum 28 so that the pull of the counterweight transmitted through it to that drum opposes the pull of the hoisting rope 17 and load 17^a is raised, and in like manner 55 reducing the wear imposed upon the brake 19, and the stress required of it in holding the load.

The operation of making a running shift 60 from a hoisting to a traversing action is extremely simple and is effected by the closing of the clutch 23. For the hoisting action, the clutch 23 is open and drums 14 and 24 are held still. The motor winds rope 17 on drum 18, and at the same time turns drum 65 28, permitting rope 27 to unwind therefrom,

and thus allowing the counterweight to descend and to aid in the raising of the load 17^a. When the desired elevation has been reached for beginning the traverse action, the operator shifts the clutch 23, and thereupon the drum 24 begins to wind rope 27 as rapidly as it is unwound from drum 28, with the result that the counterweight ceases descending. The hoisting rope 17 and the direct carriage rope 12 come in at an equal 70 rate and are wound on drums 18 and 14, while the indirect part of the carriage rope runs off of drum 14 and out through the indirect course at the same rate. When the inward end of travel is reached, the operator reverses the motor, whereupon the load will be lowered, with the counterweight helping hold the carriage stationary, if the drums 14 and 24 are held still. The running 75 of the motor thus in reverse direction winds the rope 27 on drum 28, raising the counterweight, while the rope 17 is unwound from drum 18, letting the load down. Or, dumping the load from its elevation at the inward end of travel, the starting of the 80 motor in the direction for outward travel, with clutch 23 remaining closed, reverses the action first described, with a running shift from the traverse movement to the descending movement of the bucket occurring 85 when the clutch 23 is thrown out and the brake 15 is applied.

The apparatus thus provides means for applying the counterweight to both the hoisting and the traversing ropes, reducing 90 the motive power that would be required in its absence, and provides for the operation of the apparatus without the application of rope grips or any sort of damaging frictional application to the moving parts, except at the friction brakes where such applications can be made efficiently and replaced 95 economically when worn.

It is obvious that many variations may be 100 made in the particular forms of apparatus chosen for practising the invention. The drums 24 and 28 of Fig. 1 are, for example, not necessarily on the same shafts as the drums 14 and 18, and an embodiment is 105 illustrated in Fig. 2, which does away with the extra drums altogether. In that figure, in which the way, carriage, and ropes associated therewith, and the counterweight and its ropes are seen in elevation, while the drums and their associated parts are seen in 110 plan view, the drums 14' and 18' correspond to 14 and 18 respectively of Fig. 1, and they are driven by a motor 25' and are connected by gearing 21', 22', and a clutch 23' which 115 may be a combined clutch and brake for the drum 14' operated by a single lever of any ordinary or suitable design. The peculiarity of this is that the holding rope 17' after going around its drum 18' runs off 120 on the backside to the counterweight 31' 130

which hangs in a bight thereof, and whence it runs to the drum 14', around which it passes enough to have a firm grip, and whence it runs off on the forward side as the traverse rope 12', going to the carriage, to the outer end of which it is fastened. At the same time, the other section of this rope 12' runs from the inner end of the carriage to the drum 14'. For elevation of the load, rope 17' is drawn in by drum 18' in the right of the figure, and paid out at the left, allowing the counterweight to descend, because the drum 14' is meanwhile held uncoupled and stationary by its brake. But for the running shift from hoist to traverse, the movement of the brake lever will release the brake and set the clutch so that drum 14' begins to be driven from drum 18', and the counterweight rope 27' then is wound upon drum 14' and is simultaneously run off therefrom to pay in the carriage. Thus a single rope extends from the load around the drums and the counterweight to the carriage, the counterweight acting on both load and carriage, and the shift being executed while running without any gripping or other undesirable friction of ropes.

I claim as my invention:—

1. Hoisting and transporting apparatus including a hoisting rope and a drum therefor with motor and a traversing rope and a drum therefor with brake, and with coupling to the hoisting drum, in combination with another rope and a counterweight held in a bight thereof, which counterweight rope at one end of the bight is held and moved with the said hoisting drum and at the other end of the bight is held and moved with the said traversing drum, so that during hoisting and lowering operations the counterweight is lowered and raised respectively and during transporting operations the counterweight is held stationary.

2. Hoisting and transporting apparatus including a hoisting rope and a drum therefor with motor, and a traversing rope and a drum therefor with brake, and with coupling to the hoisting drum, in combination with another rope and a counterweight held in a bight thereof; and drums, holding said counterweight rope at each end, connected severally with said first mentioned drums, and arranged to shift the counterweight rope between themselves, off of one and upon the other, when the said hoisting and traversing drums are coupled.

3. Hoisting and transporting apparatus including a hoisting rope and a drum therefor with motor, and a traversing rope and a drum therefor with brake, and with coupling to the hoisting drum, in combination with another rope and a counterweight held in a bight thereof; and additional drums, severally on the same shafts with the first mentioned drums, each holding one end of

said counterweight rope and arranged to run the two end portions of said rope in the same way of the rope when their said shafts are coupled, and to run one end only of said rope when their said shafts are not coupled together.

4. In hoisting and transporting apparatus, the combination of a way; a carriage traveling thereon; a hoisting rope depending from said carriage and a drum to which it leads; traversing ropes attached to said carriage and a traversing drum to which they lead; means for driving and controlling said hoisting and traversing drums; a counterweight rope and a counterweight suspended from a bight thereof, which counterweight rope has one end attached to said hoisting drum and its other end attached to said traversing drum so that during hoisting and lowering operations the counterweight is lowered and raised respectively, and during traversing operations, the counterweight is held stationary.

5. In a hoisting and transporting machine, the combination of a way; a carriage traveling thereon; a hoisting rope depending from said carriage; a hoisting drum to and around which said rope runs and whence it is continued as a counterweight rope; a traversing rope attached to the carriage and a traversing drum to which it runs; a second traversing rope attached to the carriage from a direction opposite to that of the first traversing rope and leading to the said traversing drum and wound around it in a direction opposite to that of the first traversing rope, and continuing thence as the other end of said counterweight rope; a floating sheave in a bight of said counterweight rope; a counterweight suspended therefrom; and means for driving and controlling said hoisting and traversing drums.

6. In hoisting and transporting apparatus, the combination of a way; a carriage traveling thereon; a hoisting rope depending from said carriage and a hoisting drum to which said rope leads; two traversing ropes attached to said carriage from opposite directions and a traversing drum to which they lead; means for driving and controlling said hoisting drum; means for coupling said traversing drum to said driving means and controlling same; a counterweight drum connected to the hoisting drum; a second counterweight drum connected to the traversing drum; a counterweight rope having its ends attached to the two counterweight drums; and a counterweight suspended from a bight in the counterweight rope.

7. In hoisting and transporting apparatus the combination of a way; a carriage traveling thereon; a hoisting rope depending from said carriage, and a hoisting drum to which said rope leads; two traversing ropes at-

tached to said carriage from opposite directions and a traversing drum to which they lead; means for driving and controlling said hoisting and traversing drums; a counterweight drum connected to the traversing drum; a counterweight rope having one end attached to the hoisting drum and its other

end attached to the counterweight drum; and a counterweight suspended from a bight in said counterweight rope. 10

Signed at New York, N. Y., this 10th day of March, 1919.

WARREN TRAVELL.
